W. H. MACK

SAW SET

Filed May 8, 1922

Inventor

W.H. Mack

By Wilkinson & Giusta

Attorney

UNITED STATES PATENT OFFICE.

WILLIAM HUGO MACK, OF OAK GROVE, LOUISIANA.

SAW SET.

Application filed May 8, 1922. Serial No. 559,489.

To all whom it may concern:

Be it known that I, WILLIAM H. MACK, a citizen of the United States, residing at Oak Grove, in the parish of West Carroll 5 and State of Louisiana, have invented certain new and useful Improvements in Saw Sets; and I do hereby declare the following to be a full, clear, and exact description of the invention, such as will enable others 10 skilled in the art to which it appertains to make and use the same.

The present invention relates to improvements in saw sets and has for an object to provide a compact conveniently operated device of economical construction in which the 15 progress of the action is open and may be clearly observed to get the desired pitch of swaging.

Other objects of the invention are to simplify the construction of saw sets generally, to provide a strong durable construction, to avoid injury to the saw teeth while accurately swaging the same and to render it a comparatively easy operation to perform 25 this work without requiring any especial skill for the task and without involving any appreciable trouble and annoyance in the conduct thereof.

With the foregoing and other objects in view, the invention will be more fully described hereinafter, and will be more particularly pointed out in the claim appended hereto.

In the drawings, wherein like symbols 30 refer to like or corresponding parts throughout the several views,

Fig. 1 is a side view of a saw set constructed according to the present invention;

Fig. 2 is a plan view of the same;

Fig. 3 is a bottom view of the device; and, 40 Fig. 4 shows a fragmentary section.

Referring more particularly to the drawings, 1 designates a beam having prongs 2 and 3 projecting downwardly at its ends to 45 take into a block, stump or the like indicated in dotted lines at 4.

The top surface of the beam 1 is generally 50 level with the exception of a curved or inclined portion 5 near one end which constitutes an anvil for receiving the teeth of the saw which are indicated at 6. Pins 7 project laterally from the beam 1 near the anvil end to act as stops for the legs 8 of a yoke member 9 having a pivotal movement 55 about a bolt or other fulcrum 10 which

passes laterally through the central portion of the beam 1 and through the free ends of the legs 8.

The head 10 of the yoke member extends upwardly at approximately right angles to the legs 8 and is provided with a pair of spaced perforated lugs 11 to slidably receive a swaging plunger 12 having an enlarged head 13 to receive blows from a hammer or other suitable implement. The plunger 12 is normally raised by the action of a coil spring 14 which is wound about the upper portion thereof and is confined between the upper lug 11 and the enlarged head 13. The upper movement of the plunger is limited by a pin 15 passing transversely therethrough and projecting into engagement with the lower surface of the upper lug 11. 65

In the use of the device, the beam 1 is initially set into a base 4, for instance a 70 stump, by driving the prongs 2 and 3 into the wood. The prong 3, as indicated in Fig. 3, is preferably provided with flat extensive sides which lie substantially parallel with the sides of the beam 1, while the prong 2 has 75 flat sides extending at right angles thereto. The prong 2 will therefore avoid any longitudinal movement or creeping of the beam, while the prong 3 will avoid lateral vibration or casual movement. In hammering 80 the prong 2 into place, the yoke may be swung upwardly about its pivot point 10 to enable access to be had to the upper surface at this point.

A saw is placed horizontally upon the 85 beam 1 with an initial tooth resting upon the anvil 5 just beneath the plunger 12. The plunger head 13 is then struck a blow with a hammer and the plunger descends 90 upon the tooth 6 and drives it down against 95 the inclined anvil surface causing it to take a proper pitch.

The spring 14 returns the plunger to the upper position in readiness for the next blow and the saw is advanced through the device 100 tooth by tooth while the above operation is repeated.

The device may be made of metal or other suitable material and it will be appreciated that with this implement, the setting of saw teeth becomes a simple matter and is attended with little effort while being carried out by one not necessarily experienced in this character of work. 105

The yoke, by virtue of its pivotal mount- 110

ing on the pin, may be lifted when the saw is removed whereby to expose the anvil surface for planing and trimming as these surfaces become pitted and uneven in use. The surfaces are entirely free from interference with the yoke as the same is pivoted centrally of the beam and swings to the opposite end of said beam.

It is obvious that various changes and 10 modifications may be made in the details of construction and design of the above specifically described embodiment of this invention without departing from the spirit thereof, such changes and modifications being restricted only by the scope of the following 15 claim.

What is claimed is:

A saw set comprising an elongated beam having means to anchor it, in a support and

provided with a sloping anvil face near one 20 end to receive the saw teeth, a yoke having legs straddling said elongated beam, a pivot passing through the inner ends of said legs and the middle portion of said beam whereby to secure the yoke to the beam and permit the swinging of the yoke from one end to the other of the beam, an upstanding head connecting the outer ends of said legs, said head having spaced lugs overlying the anvil 25 face of the beam, a plunger mounted to reciprocate in said lugs, stop means projecting from the plunger between said lugs, yieldable means to hold the plunger normally in an elevated position, and rests projecting laterally from the beam near the anvil end thereof to receive said legs for freely supporting the same and said head.

WILLIAM HUGO MACK.
